[57] CLAIM

The ornamental design for a faucet spout, as shown and described.

DESCRIPTION

FIG. 1 is a front perspective view of the faucet spout showing my new design;

FIG. 2 is a rear perspective view thereof;

FIG. 3 is a left side elevational view thereof;

FIG. 4 is a top plan view thereof;

FIG. 5 is a front elevational view thereof;

FIG. 6 is a rear elevational view thereof; and,

FIG. 7 is a bottom plan view thereof.

The broken line showing of the aerator and top of the base in FIG. 1 are for purposes of illustration only and form no part of the claimed design.
